UNITED STATES PATENTS
928,591 7/1909 Delvigne 197/91

ABSTRACT: The device includes means movable with a portion of the typewriter that moves during each actuation of a key of the typewriter. After the movable means has been moved a selected amount, the movable means is returned to its starting position. When the movable means is moved from its starting position, a resiliently biased latch is positioned to retain a backspace lever in a position for repeat operation when the backspace lever is moved to a position in which it may be retained by the latch. Whenever the movable means is returned to its starting position, the latch is moved to a non-retaining position. Thus, the device may provide backspacing for a previously typed character in a proportioned spacing typewriter or to the start of a previous word in any typewriter.

FIG. 2

MEMORY BACKSPACE DEVICE FOR PRINTING
APPARATUS
SPECIFICATION

In typewriters having proportional spacing of the characters whereby the width of each character is designed in accordance with its natural width, the spacing for each of the characters is not the same. For characters having a small natural width, the space of the type character is small in comparison with characters having a large natural width.

Therefore, when it is desired to backspace a character or a plurality of characters with a proportional spacing typewriter, the typist is required to know the number of units assigned to each character. For example, an "i" would have a width of two units while an "m" would have a width of four units. Thus, if the typist wished to backspace in a proportional spacing typewriter, it is necessary to backspace two units when the character is an "i" and four units when "m" is the character.

As a result of this requirement of the typist to remember the units of width of each of the characters of the typewriter, there has been a reluctance on the part of some typists to use a proportional spacing typewriter. Therefore, the proportional spacing typewriter has been limited, to a degree, in its utilization.

The present invention satisfactorily overcomes the foregoing problem whereby the device of the present invention does not require the typist to remember the number of units of width of each of the characters. Instead, the memory backspace device of the present invention merely requires the typist to depress the backspace lever to a second level position where it is held by retaining means of the memory device until release after the required amount of backspacing has occurred.

Furthermore, the memory device of the present invention still permits the typist to backspace only a single unit of spacing whenever desired. Thus, the memory device of the present invention not only eliminates the requirement for the typist to know the units of width of each of the characters of a proportional spacing typewriter but also allows the typist to still have single unit backspacing when desired.

It has previously been suggested in U.S. Pat. No. 928,591 to Delvigne to utilize a backspace memory device in which the typist could backspace automatically to the beginning of a word, i.e., to where a previous actuation of the space bar lever had occurred. In this type of arrangement, a rotating pin wheel structure has been employed. However, this rotating pin wheel structure has been rather complicated and relatively expensive. Furthermore, this rotating pin wheel structure is not adaptable for use in a proportional spacing typewriter in which each of the characters has varying units of width.

Thus, the present invention is an improvement over the previously suggested memory backspace device utilizing the rotating pin wheel. The memory device of the present invention is not only much simpler in construction and, therefore, relatively inexpensive, but it also may be utilized to permit selectively backspacing only a single character or a word.

In the previously suggested rotating pin wheel memory backspace device, the pin prevents any additional backspacing beyond the pin. Thus, the typist could not backspace to any position but is limited to that defined by the pin.

The present invention satisfactorily overcomes the foregoing problem since the typist can backspace any amount. Thus, backspacing is not limited to the typed word as in the previously suggested rotating pin wheel memory backspace device.

Additionally, in the previously suggested rotating pin wheel memory backspace device, separate backspace keys were required for single backspace and word backspace. The present invention permits the use of only a single backspace key for either single unit backspacing, single character backspacing, or word backspacing.

In the memory backspace device of the present invention, means is provided to automatically erase the previously stored escapement information concerning the character or word in

the memory device as soon as the next character is selected or when the space bar means is actuated. Furthermore, the present invention contemplates erasing the stored memory of escapement information concerning the character or word in response to various function operations of the typewriter such as tabulation or carriage return, for example.

An object of this invention is to provide a memory backspace device to regulate the amount of backspace of a printing apparatus in accordance with the width of the previously printed character or word.

Another object of this invention is to provide a linear memory backspace device that permits normal single unit backspacing when the backspace lever is moved to a first position and controlled automatic back spacing in accordance with the stored memory of the prior typed character or word when the backspace lever is moved to a second position.

A further object of this invention is to provide a memory backspace device that is relatively inexpensive and may be easily added to a typewriter.

The foregoing and other objects, features, and advantages of the invention will be more apparent from the following more particular description of the preferred embodiments of the invention as illustrated in the accompanying drawing.

In the drawing:

FIG. 1 is a schematic perspective view of one embodiment of the memory backspace device of the present invention and taken from the rear of a typewriter.

FIG. 2 is a schematic perspective view of a portion of the backspace mechanism utilized with the device of the present invention.

FIG. 3 is a schematic perspective view of another portion of the backspace mechanism.

FIG. 4 is a schematic perspective view of another form of the memory backspace device of the present invention and taken from the rear of a typewriter.

FIG. 5 is a schematic perspective view of a modification of a portion of the device of FIG. 1.

Referring to the drawing and particularly FIG. 1, there is shown a movable member 10 of a typewriter. In a typewriter having typebars for printing characters, the movable member 10 may be attached to the carriage bed, for example, which moves with the platen supporting the paper upon which printing occurs as the platen moves relative to a reference position at which each character is printed by its typebar. The movable member 10 functions as a movable letter feeding part.

The memory backspace device of the present invention includes a memory bracket 11 having a memory lever 12 universally mounted thereon, and the memory lever 12 has a friction member 14 supported on one end thereof with a surface 15 of the friction member 14 engaging the bottom of the movable member 10. The friction member 14 is preferably formed of a suitable friction material such as asbestos filled rubber, for example, that will cause the memory lever 12 to follow the movement of the movable member 10 to the right until the memory lever 12 engages a stop 16 on the bracket 11 or to follow the movement of the member 10 to the left until the memory lever 12 engages a second stop 17 on the memory bracket 11. When the lever 12 engages either of the stops 16 and 17 depending on the direction of movement of the movable member 10, the friction member 14 permits the movable member 10 to continue to move relative to the memory lever 12.

The memory bracket 11, which is fixedly secured to a fixed portion of the typewriter, has a flange 18 disposed parallel to main surface 19 of the memory bracket 11 and in spaced relation thereto. A block 20 is pivotally mounted between the flange 18 and the main surface 19 by a pin 21.

The block 20 pivotally mounts the memory lever 12 thereon by a pin 22, which is disposed substantially perpendicular to the pin 21, whereby the memory lever 12 may pivot about the axis of the pin 22. Since the block 20 may pivot about the axis of the pin 21, the memory lever 12 is universally mounted on the bracket 11.

The memory lever 12 is biased upwardly and to the left by a spring 23. The movement to the left is in the direction of backspace movement. The spring 23 has one end secured to a downwardly depending finger 24 on the memory bracket 11 and its other end secured to a horizontally upstanding finger 25 on the memory lever 12.

Thus, the spring 23 serves to continuously urge the surface 15 of the friction member 14 into engagement with the movable member 10. At the same time, the spring 23 continuously urges the lever 12 against the stop 17. The force of the spring 23 is overcome by the movement of the movable member 10 as the paper is moved relative to the reference position at which the characters are typed.

The typewriter has a backspace lever 26, which is pivotally mounted on a rod 27 fixed to the frame of the typewriter. The front end of the backspace lever 26 extends through a slot 28 in a front guide comb 29, which is fixed to the typewriter. The backspace lever 26 is continuously urged upwardly (as viewed in FIGS. 2 and 3) about the rod 27 by a spring 30, which has one end connected to the front end of the backspace lever 26 and its other end connected to a projection 31 (see FIG. 3) on the front guide comb 29 with the projection 31 disposed vertically above the slot 28.

A plunger 32 is continuously urged against the bottom surface of the guide comb 29 by a spring 33, which has its lower end bearing on a projection 34 on the lower portion of the front guide comb 29. The lower end of the slot 28 is open in the same manner as is shown for a slot 35 in the front guide comb 29. Thus, when the backspace lever 26 is depressed through actuation of its keybutton 36, the backspace lever 26 may move through the slot 28 and move the plunger 32 downwardly against the force of the spring 33 from a first level position to a second level position. The upper end of the plunger 32 is U-shaped to cooperate with the front guide comb 29 to be moved only vertically.

The backspace lever 26 is connected through a cam assembly 37 (see FIG. 2), which is fulcrumed on a rod 38 that is fixedly secured to the typewriter, and an operating link 39 to a backspace mechanism. If the memory backspace device of the present invention is being utilized with a conventional typebar typewriter in which each of the characters has the same type width, the backspace mechanism is preferably of the type shown and described in pages 99 to 103 of IBM Customer Engineering Instruction Manual for Standard Typewriter, Model C-1, Copyrighted 1960. If the device is used with a proportional spacing typewriter in which each type character has a width in accordance with its natural width, then the backspace mechanism would be of the type shown and described in pages 51 to 58 or the type shown and described in pages 59 and 60 of the IBM Customer Engineering Instruction Manual for "Executive" Typewriter, Model C-4, Copyrighted 1961.

The backspace lever 26 is connected to a release lever 40 of the cam assembly 37 by a cam release link 41 and a cam release lever spring 42. As more particularly shown and described in pages 49 to 52 of the aforesaid IBM Model C-1 Manual, the cam assembly 37 has a single lobed cam 43 rotatably mounted thereon for cooperation with the power roll of the typewriter. The single lobed cam 43 rotates 360° during each actuation thereof.

The cam release lever 40 has a primary forward lug and a nonrepeat lug thereon for cooperation with a cam lug on the cam 43. When the backspace lever 26 is moved to its second level position whereby the plunger 32 is moved downwardly against the force of the spring 33, the nonrepeat lug of the release lever 40 is maintained out of the path of the cam lug to permit automatic repeat operation of the backspace mechanism. This cooperation between the lugs on the cam release lever 40 and the lug on the cam 43 is particularly described on page 51 of the aforesaid IBM Model C-1 Manual. The type of cooperation between the backspace lever 26 and nonrepeat lug of the cam release lever 40 also is mentioned on page 87 of the aforesaid IBM Model C-1 Manual with respect to the carriage return key lever. This same operation occurs with the backspace lever 26.

Accordingly, the initial downward movement of the backspace lever 26 results in the lever 26 merely moving the plunger 32 downwardly but not sufficiently to overcome the force of the spring 33. This results in a first level position for the backspace lever 26 whereby a single actuation of the backspace mechanism of the typewriter occurs to backspace the carriage and the platen relative to the reference position at which the characters are printed. This backspace movement moves the movable member 10 to the left.

10 When additional force is exerted by the typist on the backspace lever 26, the force of the spring 33 is overcome to permit further downward movement of the backspace lever 26 to a second level position. In this second level position of the backspace lever 26, repeat backspace operations of the backspace mechanism occur due to the position of the nonrepeat lug on the release lever 40 until the backspace lever 26 is released.

15 In the present proportional spacing typewriters, the typist must know the number of units that each character occupies and backspace this number of units for each character when that character has been erased, for example, due to an error. This may be accomplished by single actuation of the backspace lever 26 or by the typist holding the backspace lever 26 in its second level position until the required number of backspace operations has occurred.

20 The memory backspace device of the present invention utilizes a latch 50 to retain the backspace lever 26 in its second level position until the required number of repeat backspace operations has occurred to move the carriage to the desired position. For example, if the memory backspace device of the present invention is utilized to produce a selected amount of backspacing in accordance with the width of the character previously typed, then the latch 50 would retain the backspace lever 26 in its second level position until the selected amount of backspacing has occurred. Similarly, if a word is the selected amount of backspacing desired, then the latch 50 would retain the lever 26 in its second level position until this amount of backspacing has occurred. It should be understood that the latch 50 cannot retain the lever 26 in its second level (repeat backspace operation) position until the lever 26 has been moved to its second level position by the typist.

25 The latch 50, which is pivotally mounted on a rod 50', is resiliently biased into engagement with the lever 26 by a spring 51. However, the latch 50 abuts against the side of the lever 26 rather than latching over the top surface thereof in either the normal rest position of the lever 26 or the position of the lever 26 when single actuation is produced. Thus, the latch 50 cannot affect the operation of the backspace lever 26 until the lever 26 is moved to its second level position whereby automatic repeat backspace operations may occur.

30 The latch 50 is connected through a cable or wire 52 to the finger 25 of the memory lever 12. The cable 52, which has one end connected to the latch 50, is enclosed along its entire length by a sheath 53 (removed along most of the cable 52 for clarity purposes), which has a portion supported in a bracket 54 that is fixed to the typewriter frame and clamped to the bracket 54. The other end of the cable 52, which is slidably supported in the sheath 53, is connected to the finger 25 of the memory lever 12 by a hook portion 55. The portion 55 extends through an enlarged opening or elongated slot 57 in the finger 25 of the memory lever 12 and is of a length to permit pivoting of the memory lever 12 about the pin 22 without affecting the position of the cable 52. Thus, only pivotal movement of the lever 12 about the pin 21 is transmitted to the latch 50.

35 The pivotal movement of the lever 12 about the pin 22 is limited because of the engagement of the bottom of the lever 12 with the main surface 19 of the bracket 11 and engagement of the surface 15 of the frictional member 14 with the bottom of the movable member 10. This permits only a limited amount of pivotal movement of the memory lever 12 about the pin 22.

40 The latch 50 is shown in its nonretaining position in FIG. 1 due to the memory lever 12 engaging the stop 17. In this posi-

tion of the memory lever 12, the cable or wire 52 holds the latch 50 away from the position in which it will retain the backspace lever 26 in its second level position when the lever 26 is moved to its second level position.

Accordingly, whenever the cable or wire 52 is moved due to clockwise pivoting of the lever 12 about the pin 21 so that the lever 12 moves away from the stop 17, the latch 50 is moved by the spring 51 to the position in which the latch 50 abuts against the side of the lever 26. This clockwise pivoting of the lever 12 about the pin 21 occurs when the movable member 10 is moved to the right due to printing occurring because of the paper on which the characters are being printed being moved in a forward horizontal direction relative to the reference position at which characters are to be printed.

When the memory lever 12 is returned into engagement with the stop 17 by counterclockwise pivoting of the lever 12 about the pin 21, the cable 52 pulls the latch 50 to its non-retaining position. Thus, the cable 52 regulates when the latch 50 is moved to and from its nonretaining position with the lever 12 controlling this regulating means.

When used with a proportional spacing typewriter, the memory lever 12 may be moved with the movable member 10 for either the amount of movement of the member 10 to the right due to a single character being typed or a word being typed. Thus, the selected amount of movement of the memory lever 12 by the movable member 10 before the memory lever 12 is removed from engagement therewith may be either the width of the character typed or the width of the word typed. Of course, with a conventional typewriter, the selected amount of movement of the memory lever 12 would only be a word since single actuation of the backspace means for a conventional lever would produce the desired amount of backspacing for any single typed character.

In moving the memory lever 12 either the amount due to a single character being typed or a word being typed, the memory lever 12 is moved to one of a plurality of effective positions from its home position, which is the position when the memory lever 12 is engaging against the stop 17 and to which it is always returned. When the memory lever 12 is disengaged from the movable member 10, it returns to the home position. Therefore, the memory lever 12 reciprocates between the home position and one of the effective positions, which represents either a character or word being typed, to which it is moved during movement of the movable member 10.

If the selected amount of movement of the memory lever 12 is the typed word, then the memory lever 12 would be permitted to move with the movable member 10 until after completion of the word. Completion of the word has occurred when a spacebar lever is actuated.

When this occurs, the memory lever 12 is pivoted clockwise about the pin 22 and counterclockwise about the pin 21 to return the memory lever 12 to the position in which it abuts against the stop 17. Of course, when the surface 15 of the friction member 14 is removed from engagement with the movable member 10, the spring 23 also aids in moving the memory lever 12 counterclockwise about the pin 21 so that the pivoting of the memory lever 12 about the pin 21 is both by the operating mechanism, which is responsive to the spacebar lever to exert a pulling force on the memory lever 12, and the spring 23.

The operating mechanism for removing the surface 15 of the friction member 14 from engagement with the movable member 10 and returning the memory lever 12 into engagement with the stop 17 includes a cable or wire 58, which is enclosed within a sheath 59 (partially shown for clarity purposes) and slidably movable therein. The sheath 59 is supported within a curved portion of a bracket 60, which is fixed to an upstanding portion 61 of the bracket 11, and clamped thereto. The cable or wire 58 has one end connected to the memory finger 25 and its other end directly or indirectly connected to the spacebar mechanism of the typewriter. Thus, when the spacebar mechanism is actuated by the typist to in-

dicate the end of a word, the cable or wire 58 pulls the finger 25 of the memory lever 12 upwardly and to the right due to the angle of force exerted by the cable 58 with respect to the finger 25 whereby the lever 12 pivots clockwise about the pin 22 and counterclockwise about the pin 21 to return the lever 12 to the position in which it engages against the stop 17.

As shown in FIG. 1, the other end of the cable 58 is formed as a looped portion 61a cooperating with a bail 61b, which extends therethrough and is actuated when the spacebar mechanism is actuated by the typist. The looped portion 61a of the cable 58 is selected so that the lever 12 may move from the stop 17 to the stop 16, but the movement of the bail 61b causes return of the lever 12 into engagement with the stop 17.

As soon as the memory lever 12 is moved away from engagement with the stop 17, this initial clockwise movement of the memory lever 12 about the pin 21 results in the cable 52 no longer holding the latch 50 in its nonretaining position but permits the spring 51 to urge the latch 50 into the position in which it abuts against a side of the backspace lever 26. Thus, as soon as the memory lever 12 leaves its abutting position against the stop 17, the latch 50 is moved to the position in which it may readily retain the backspace lever 26 when the lever 26 is in its second level position.

When the spacebar lever is actuated, the cable or wire 58 returns the memory lever 12 to the position in which it abuts against the stop 17. Thus, the cable 52 pulls the latch 50 clockwise against the force of the spring 51 to dispose the latch 50 in a nonretaining position.

When the memory lever 12 is moved away from the stop 17 by the movable member 10, movement of the backspace lever 26 into its second level position wherein automatic repeat backspace operations will occur as long as the lever 26 is held in this position results in the latch 50 retaining the backspace lever 26 in its second level position until the memory lever 12 is returned to the position in which it abuts against the stop 17. Thus, as backspacing progresses, the member 10 moves to the left to return the memory lever 12 into engagement with the stop 17. As soon as it reaches this position, which indicates the starting position of the word, the cable 52 pulls the latch 50 to its nonretaining position to release the backspace lever 26 whereby the backspace lever 26 returns to its rest position by the force of the spring 30.

If any of the words being typed should have an exceedingly long length, then the memory lever 12 would abut against the stop 16. Thus, the total pivotal movement of the memory lever 12 is limited to a predetermined amount.

If the memory backspace device of the present invention is to be utilized on a proportional spacing typewriter, it might be preferable to move the memory lever 12 only the width of each typed character. Since the width of each of the characters would vary depending on the natural width of the character, this would result in a varying amount of movement of the memory lever 12 by the movable member 10 depending upon the natural width of the character being typed.

In this arrangement, the cable 58 would be connected to a portion of the mechanism actuated during each actuation of a character key. In order that the previously stored character width in the memory device may be removed, it is preferred to actuate the cable 58 when the ribbon lift begins to move during selection of a character. This permits the friction surface 15 of the friction member 14 to be released from engagement with the movable member 10 and returned to a position abutting against the stop 17 before the character is printed at the reference position. This arrangement insures that the memory lever 12 remains in a position in which the latch 50 abuts against the side of the backspace lever 26 with the position of the memory lever 12 from the stop 17 being the number of units of space in accordance with the previously typed character until the next character is being selected.

When the lever 12 is to be advanced only the width of the typed character, the bail 61b would be the ribbon lift bail. Thus, the looped portion 61a of the cable 58 would allow the

lever 12 to move from the stop 17 to the stop 16 without the cable 58 retarding movement thereof while the actuation of the bail 61b still results in the lever 12 being returned into engagement with the stop 17.

Thus, when a character is typed, the memory lever 12 is moved away from engagement with the stop 17. The lever 12 remains away from the stop 17 wherein the latch 50 is held against the side of the backspace lever 26 by the spring 51 until the ribbon lift begins to move during selection of the next character. At this time, the cable 58 and the spring 23 move the memory lever 12 back to its position against the stop 17 whereby the cable 52 moves the latch 50 to its nonretaining position. Then, as the character is typed, the movable member 10 moves the width of the new character and carries the memory lever 12 therewith away from the stop 17.

This movement of the memory lever 12 away from the stop 17 allows the spring 51 to move the latch 50 into engagement with the side of the backspace lever 26. If at the end of the typed letter, an error is made, depression of the backspace lever 26 to its second level position results in the latch 50 retaining the backspace lever 26 in its second level position until the movable member 10 has moved to the left sufficiently to return the memory lever 12 into engagement with the stop 17. At this time, the cable 52 pulls the latch 50 to its nonretaining position and allows the backspace lever 26 to be returned to its rest position.

The memory lever 12 also is returned into engagement with the stop 17 when various function operations of the typewriter occur. Thus, if a carriage return or tabulation occurs, for example, the memory lever 12 is returned into engagement with the stop 17 irrespective of whether the memory lever 12 has been moved the selected amount by the movable member 10. This results in removal of the stored memory in the memory lever 12.

The finger 25 of the memory lever 12 has one end of a second cable 62 connected thereto. The second cable 62 is enclosed within a sheath 63 (partially shown for clarity purposes), which is supported in another curved portion of the bracket 60 and clamped thereto. The other end of the cable 62, which is slidably supported within the sheath 63, is connected to means responsive to the various function operations. For example, the cable or wire 62 could be connected to the carriage return or to the tabulation lever or be responsive to movement of either.

The other end of the cable 62 may be formed in a looped portion 62a cooperating with a bail 62b, which extends therethrough. The bail 62b may be responsive to any of the various function operations of the typewriter by having the bail 62b span all of the cams producing the various function operations so that the bail 62b is responsive to any of the function operations.

Accordingly, when the cable 62 is moved, the lever 12 is pivoted clockwise about the pin 22 to remove the surface 15 of the friction member 14 from engagement with the movable member 10, and the lever 12 is pivoted counterclockwise about the pin 21 to return the lever 12 into abutting engagement with the stop 17. When this occurs, the previously stored character, word, or portion of the word in the memory lever 12 is removed. As a result, the return of the memory lever 12 into engagement with the stop 17 by the cable 62 due to a function operation of the typewriter results in the latch 50 being moved to its nonretaining position by the cable 52. Accordingly, depression of the backspace lever 26 to its second level position would not result in the backspace lever 26 being retained in its second level position by the latch 50.

While the memory lever 12 has the friction surface 15 of the friction member 14 in engagement with the movable member 10 to follow the movement thereof during backspace operations, it should be understood that the friction surface 15 has a coefficient of friction with the member 10 so that manual movement of the member 10 to the left permits sliding of the member 10 relative to the friction surface 15 when the memory lever 12 abuts against the stop 17. Thus, the memory

lever 12 does not retard movement of the movable member 10 and the connected platen.

Considering the operation of the device of FIG. 1, the spring 23 normally urges the memory lever 12 to the position shown 5 wherein the memory lever 12 abuts against the stop 17 and the friction surface 15 of the friction member 14 is held in contact with the movable member 10. In this position of the memory lever 12, the latch 50 is held in a nonretaining position by the cable 52 whereby movement of the backspace lever 26 to its 10 second level position does not result in the backspace lever 26 being retained in its second level position by the latch 50.

If the selected amount of movement of the memory lever 12 is a typed character, then the memory lever 12 moves with the movable member 10 for the distance that the movable member 10 moves to type the single character. Any movement of the memory lever 12 away from the position of FIG. 1 results in the spring 51 urging the latch 50 into engagement with the side of the backspace lever 26.

If an error should be made by the typist in typing the 20 character, erasure of the character may be accomplished by rotating the platen to advance the paper vertically relatively to the reference position at which the character is typed. After the character has been erased and the paper returned to the position in which the character was printed at the reference 25 position, it is now necessary to return the platen and the paper to the position at which printing of the erased character started. Accordingly, depression of the backspace lever 26 to its second level position results in the latch 50 retaining the backspace lever 26 in this position in which automatic repeat 30 backspace operations occur until the memory lever 12 has been returned into engagement with the stop 17 by the movable member 10. This amount of rearward movement (to the left) by the movable member 10 and the memory lever 12 is equal to the amount of forward movement produced during 35 typing of the character. Accordingly, when the lever 12 abuts against the stop 17, the cable 52 exerts a force to pull the latch 50 to its nonretaining position whereby the backspace lever 26 returns to its rest position due to the force of the springs 30 and 33.

When the memory lever 12 is removed from engagement 40 with the stop 17 by the movable member 10 to allow the latch 50 to be moved by the spring 51, it should be understood that the latch 50 will not retain the backspace lever 26 until the 45 backspace lever 26 is moved to its second level position. That is, the backspace lever 26 may be depressed against the plunger 32 by the typist to a first level position in which single actuation of the backspace mechanism occurs. Thus, the latch 50 permits single actuation of the backspace lever 26 even 50 when the latch 50 is in engagement with the backspace lever 26 since the latch 50 cannot retain the backspace lever 26 until the lever 26 is moved to its second level position.

If a word is to be the selected amount of movement of the 55 memory lever 12 rather than each typed character, then the cable 58 would be connected to be responsive to the spacebar means, which is utilized whenever a word is completed, rather than being responsive to the ribbon lift mechanism. Thus, the memory lever 12 would be moved by the movable member 10 until the spacebar means is actuated. When this occurs, the 60 memory device 12 will be returned to the position in which it abuts against the stop 17 whereby the latch 50 is held in its nonretaining position by the cable 52.

With the memory lever 12 being moved by the movable 65 member 10 until the end of a typed word, any error in typing the word could be corrected by erasing the entire word. Then, depression of the backspace lever 26 to its second level position would result in the latch 50 holding the lever 26 in this repeat position until the memory lever 12 is returned into engagement with the stop 17 by the movable member 10 moving 70 to the left due to backspacing operation causing the platen carrying the paper on which the characters are printed to move to the left.

When the memory lever 12 engages the stop 17, the paper is positioned at the reference position. This permits typing to 75 begin again where the erased word originally started.

Of course, as described with respect to the memory lever 12 being moved only the width of a character in a proportional spacing typewriter rather than each typed word, the backspace lever 26 may be moved to a first position in which it abuts against the plunger 32 for single backspacing without the latch 50 retaining the backspacing lever 26. However, the latch 50 is disposed in engaging position with the side of the backspace lever 26 and will retain the backspace lever 26 whenever the backspace lever 26 is moved to its second level position by overcoming the force of the spring 33 to depress the plunger 32 further downwardly.

Irrespective of whether the memory lever 12 is moved a selected amount depending on the width of the character typed or the width of the word typed, the memory lever 12 is returned to its position against the stop 17 whenever the cable 62 is actuated. This results in the latch 50 being moved to its nonretaining position.

By having the cable 62 responsive to various function operations, the stored memory in the memory lever 12 is removed as soon as a function operation occurs. Thus, for example, if a carriage return occurs, the cable 62 is actuated to return the memory lever 12 into engagement with the stop 17. Additionally, this actuation of the cable 62 results in the friction surface 15 not engaging the movable member 10 during movement of the movable member 10 to the left because of carriage return. While such movement would be possible even if the friction surface 15 were engaging the movable member 10, it is desirable to not have the friction surface 15 engaging the movable member 10 to reduce wear of the friction surface 15.

Referring to FIG. 4, there is shown another embodiment of the backspace memory device of the present invention in which a memory wheel 70 cooperates with the movable member 10. The memory wheel 70 has a friction surface formed thereon of a suitable friction material, which is preferably the same as the friction member 14.

The wheel 70 is fixedly mounted on a rotatably mounted shaft 71. One end of the shaft 71 is rotatably supported in a bracket 72, which is fixedly secured to the frame of the typewriter. The other end of the shaft 71 is rotatably supported by a bellcrank lever 73, which is pivotally mounted on a rod 74. The rod 74 is fixedly secured to the frame of the typewriter.

A spring 75, which has one end secured to a fixed portion 76 of the frame of the typewriter and its other end secured to the bellcrank lever 73, continuously urges the memory wheel 70 into engagement with the movable member 10. Thus, the memory wheel 70 follows the movement of the movable member 10 as long as the bellcrank lever 73 is held in the position of FIG. 4 by the spring 75.

When the force of the spring 75 is overcome, the bellcrank lever 73 is rotated counterclockwise about the rod 74 to remove the memory wheel 70 from engagement with the movable member 10. A link 77, which is slidably supported by a bracket 77', is connected to the bellcrank lever 73, and movement of the link 77 to the right causes the bellcrank lever 73 to pivot counterclockwise against the force of the spring 75.

Unless the link 77 is moved to the right, the spring 75 retains the memory wheel 70 in engagement with the movable member 10 whereby the memory wheel 70 rotates clockwise when the movable member 10 moves to the right and counterclockwise when the movable member 10 moves to the left. The movement of the movable member 10 to the right occurs when the paper on which the type characters are printed is being advanced forwardly in a horizontal direction relative to the reference position at which the type characters are printed. The movement to the left of the movable member 10 occurs when backspacing occurs.

The shaft 71 has a pulley 78 fixedly secured thereto for rotation therewith. Thus, any rotation of the shaft 71 by the memory wheel 70 is transmitted to the pulley 78.

A tape 79 passes around the pulley 78 and also passes around an idler pulley 80, which is rotatably mounted on a rod

81 fixed to the frame of the typewriter. The tape 79 has sufficient friction contact with the pulley 78 to move therewith.

The tape 79 passes through an opening 82 in a bracket 83, which is fixed to the frame of the typewriter, and an opening 84 in a bracket 85, which also is fixed to the frame of the typewriter. A tape spring 86 surrounds the tape 79 and has one end fixed to the bracket 83. The other end of the tape spring 86 bears against a bead 87 on the tape 79 with the bead 87 being larger than the opening 84. As the memory wheel 70 is rotated clockwise, the tape spring 86 is compressed by the bead 87 moving toward the bracket 83.

The tape 79 has a second bead 88 thereon for cooperation with a latch 89, which cooperates with the backspace lever 26 to retain the backspace lever 26 in its second level position when the latch 89 is in its retaining position and the backspace lever 26 is in its second level position. The latch 89 is formed of resilient material so that it is spring biased into engagement with the backspace lever 26.

The latch 89 has an opening 90 therein through which the tape 79 passes. However, the size of the opening 90 prevents the bead 88 from passing therethrough. Accordingly, when the bead 88 engages the latch 89, the latch 89 has its resilient force overcome and is removed from its position against the side of the backspace lever 26.

Accordingly, clockwise rotation of the memory wheel 70 by the movable member 10 moves the bead 88 away from engagement with the latch 89 whereby the latch 89 abuts against the side of the backspace lever 26 for movement to its retaining position when the backspace lever 26 is moved to its second level position. This clockwise rotation of the memory wheel 70 also results in the tape spring 86 being compressed by the bead 87. This occurs when characters are being typed.

When the movable member 10 is moved to the left (This is backspace movement.), the memory wheel 70 is moved counterclockwise by the member 10 whereby the bead 88 is eventually moved into engagement with the latch 89 to remove it from its retaining position. This occurs when the backspace lever 26 is depressed.

The embodiment of FIG. 4 is shown for use with a proportional spacing typewriter in which the width of each character is designed in accordance with its natural width. Thus, the memory backspace device of FIG. 4 contemplates the memory backspace device storing either a character or a word in accordance with the desire of the typist.

As previously mentioned, movement of the link 77 to the right removes the memory wheel 70 from engagement with the movable member 10. When this occurs, the tape spring 86 causes counterclockwise rotation of the memory wheel 70 and the pulley 78 until the bead 87 engages the bracket 85. When this occurs, the bead 88 has moved the latch 89 to its nonretaining position.

The link 77 may be moved to the right whenever an annular member 91 on the link 77 is engaged by an arm 92, which is pivotally mounted by a pin 92a on a bifurcated member 92b, or an arm 93, which is pivotally mounted by a pin 93a on a bifurcated member 93b, and moved to the right. The arm 92 is responsive to the movements of the ribbon lift mechanism and extends through an opening in a pivotally mounted lever 94. The lever 94, which has the link 77 passing through an elongated slot 95 therein, is shown in FIG. 4 in position to have a finger 96 on the arm 92 disposed for engagement with the annular member 91. Thus, in the position shown in FIG. 4, each movement of the ribbon lift mechanism results in the link 77 being moved to the right due to the arm 92 being moved to the right whereby the finger 96 pulls the annular member 91 therewith.

A resiliently biased latch 97 is disposed in a notch 98 in a top surface of the lever 94 in the position of FIG. 4. In this position, the lever 94 is retained by the latch 97 so as to insure that the finger 96 of the arm 92 engages the annular member 91.

When the latch 97 is disposed in a notch 99 in the lever 94 due to leftward movement of the lever 94, a finger 100 on the

arm 93 engages the annular member 91 of the link 77 rather than the finger 96 of the arm 92. The arm 93 is connected to the spacebar lever of the typewriter whereby each actuation of the spacebar lever moves the arm 93 to the right. As a result, the finger 100 moves the annular member 91 and the connecting link 77 to the right whereby the bellcrank lever 73 is pivoted counterclockwise to remove the memory wheel 70 from engagement with the movable member 10.

Accordingly, the embodiment of FIG. 4 permits the typist to determine whether the memory backspace device is effective for each character or for each word typed. It should be understood that the lever 94 would be connected by suitable means to a mechanism disposed on the exterior of the typewriter for actuation by the typist.

As shown in FIG. 4, the lever 94 has a rod 100a disposed in one end thereof and connected to a control lever 100b, which is exterior of the typewriter frame for actuation by the typist. The control lever 100b is pivotally supported on a rod 100c. Accordingly, when the control lever 100b pivots about the axis of the rod 100c, the lever 94 also pivots about the axis of the rod 100c to move longitudinally from the position of FIG. 4 to the left.

Considering the operation of the memory backspace device of FIG. 4 with the lever 94 in the position shown in FIG. 4, movement of the movable member 10 to the right during typing operations causes clockwise rotation of the memory wheel 70. Clockwise rotation of the memory wheel 70 results in the bead 88 being removed away from the latch 89 as soon as the movable member 10 moves. As the actuation of the next character key results in the ribbon lift a result, the latch 89 moves to the position in which it abuts against the side of the backspace lever 26. This clockwise movement of the memory wheel 70 causes compression of the tape spring 86.

With the lever 94 positioned for each character to be the selected amount of movement of the memory wheel 70, the actuation of the next character key results in the ribbon lift mechanism causing the link 77 to move to the right through the arm 92 whereby the memory wheel 70 is released from engagement with the movable member 10 before printing of the next character but during actuation thereof. As soon as the memory wheel 70 is released from engagement with the movable member 10 due to counterclockwise pivoting of the bellcrank lever 73, the tape spring 86 rotates the pulley 78 and the memory wheel 70 counterclockwise until the bead 87 engages the bracket 85. This movement of the tape spring 86 returns the bead 88 into engagement with the latch 89 to move the latch 89 to its nonretaining position.

When the next character is printed, the movement of the movable member 10 to the right again causes clockwise rotation of the memory wheel 70. This again removes the bead 88 from engagement with the latch 89 to allow the latch 89 to be disposed against the side of the backspace lever 26.

If an error should occur when typing this letter, the typist would vertically move the paper relative to the reference or printing position by rotating the platen and erase the character. Then, the paper would again be properly aligned to permit printing of a character thereon. At this time, the typist would depress the backspace lever 26 to its second level position by overcoming the force of the spring 33. When the backspace lever 26 moves to its second level position, the latch 89 would retain the backspace lever 26 in this second level position until backspacing is completed for the particular width of the previously typed character.

Each actuation of the backspacing mechanism moves the movable member 10 to the left whereby the memory wheel 70 rotates counterclockwise and moves the bead 88 closer to the latch 89. When the final backspace occurs, the bead 88 engages the latch 89 to move the latch 89 to its nonretaining position and release the backspace lever 26. At this time, the typist may type the correct character.

If the typist wishes to utilize the memory backspace device for only words, then the lever 94 is moved so that the latch 97 is disposed in the notch 99. At this time, the arm 93 has the

finger 100 disposed for engagement with the annular member 91 and the finger 96 of the arm 92 is disposed so as to not engage the annular member 91 during movement of the arm 92 to the right during each ribbon lift operation.

With the lever 94 appropriately positioned for words rather than characters, the memory wheel 70 rotates clockwise with the movable member 10 until the spacebar means is actuated. When this occurs, the link 77 is moved to the right by the finger 100 of the arm 93 whereby the memory wheel 70 is released from engagement with the movable member 10. The compressed tape spring 86 then rotates the pulley 78 and the memory wheel 70 counterclockwise until the bead 87 engages the bracket 85. At this time, the bead 88 has engaged the latch 89 to move it to its nonretaining position.

When typing of another word begins, the memory wheel 70 is again rotated clockwise by the movable member 10 moving to the right to again remove the bead 88 from engagement with the latch 89. This permits the latch 89 to again return to the position in which it may retain the backspace lever 26 in its second level position when the lever 26 is moved to this position.

If the typist should make an error in the work, the paper is moved vertically by rotating the platen to permit erasure of the entire work. Then, the paper is again returned to the position in which printing occurs.

Depression of the backspace lever 26 to its second level position at this time results in the backspace lever 26 being retained by the latch 89 until there has been sufficient rearward horizontal movement of the paper on which the characters are printed relative to the reference position at which the characters are typed. When the rearward relative horizontal movement has resulted in the paper being positioned so that typing may occur where the word previously began, the bead 88 has engaged the latch 89 to move it to its nonretaining position. At this time, the backspace lever 26 is returned to its rest position by the spring 33.

During backspacing by the backspace means, the movable member 10 moves to the left. Due to this movement of the movable member 10 to the left, the memory wheel 70 rotates counterclockwise to eventually return the bead 88 into engagement with the latch 89.

If it is desired to return the latch 89 to its nonretaining position during each function operation of the typewriter irrespective of the selected amount of movement of the memory wheel 70, the link 77 may have a second annular member 101 thereon for cooperation with a finger 102 on an arm 103. Thus, when the arm 103 is moved to the right, the link 77 is pulled to the right whereby the memory wheel 70 is released from engagement with the movable member 10. As a result, the tape spring 86 returns the tape 79 to the position in which the bead 88 engages the latch 89 to return the latch 89 to its nonretaining position.

The arm 103 may be made responsive to any desired functional operation of the typewriter. For example, the arm 103 could be responsive to tabulation or carriage return, for example. The connection to the arm 103 could be in such a manner that it could be responsive to either of these function operations if desired.

It should be understood that the amount of pivotal movement of the bellcrank lever 73 is very slight. The shaft 71 is rotatably supported in the fixed bracket 72 so that the actual amount of movement of the shaft 71 is quite limited.

When the bead 88 is in engagement with the latch 89, the memory wheel 70 is at its start or home position to which it always returns. The memory wheel 70 is moved by the movable member 10 to one of a plurality of effective positions depending upon whether the memory wheel 70 is rotated a distance equal to the width of a typed character or the width of a typed word; thus, the memory wheel 70 is advanced to a plurality of effective positions from its home position.

The memory wheel 70 is returned to the home position when the memory wheel 70 is disengaged from the movable member 10. Thus, the memory wheel 70 reciprocates between

its home position and one of the effective positions to which it is moved by the movable member 10.

If there should be movement of the member 10 to the left due to manual movement of the carriage or the arm 103 should not be employed, the movement of the member 10 to the left by movement of the carriage results in returning the bead 88 into engagement with the latch 89 and the bead 87 into engagement with the bracket 85. This removes any stored memory in the device.

The engagement of the bead 88 with the latch 89 and the bead 87 with the bracket 85 stops further counterclockwise rotation of the shaft 71 due to the wheel 70 being rotated counterclockwise by the movement of the member 10 to the left. As a result, traction engagement between the movable member 10 and the wheel 70 ceases because of the wheel 70 being prevented from rotating. This breaking of the traction engagement between the movable member 10 and the wheel 70 results in the movable member 10 continuing to move to the left without any rotation of the wheel 70.

While the embodiment of FIG. 1 has been described for controlling the amount of movement of the memory lever 12 in accordance with only the width of the typed character or a typed word depending on whether the cable 58 is connected only to the ribbon lift mechanism or the spacebar means of the typewriter, it should be understood that the cable 58 may be made responsive to either the ribbon mechanism or the spacebar means as described for the modification of FIG. 4. Thus, suitable means would be employed to cooperate with the cable 58 to actuate it in response to either the ribbon lift mechanism or the spacebar means in accordance with means controlled by the typist.

Referring to FIG. 5, there is shown an arrangement for actuating the cable 58 in response to either the ribbon lift mechanism or the space bar means. The cable 58 is connected to a link 110 with an annular member 111 on one end thereof. The link 110 is pivotally connected to the cable 58 for movement by a control lever 112, which the typist controls, between a position in which the annular member 111 may be engaged by a finger 113 on an arm 114 and a position in which the annular member 111 may be engaged by a finger 115 on an arm 116.

The arm 114 is responsive to the movement of the ribbon lift mechanism. Thus, each movement of the ribbon lift mechanism in the link 110 being moved to the right due to the arm 114 being moved to the right when the link 110 is disposed so that the finger 113 can engage the annular member 111 when the arm 114 moves to the right. This pulls the cable 58 to return the memory lever 12 into engagement with the stop 17.

The arm 116 is connected to the space bar lever of the typewriter whereby each actuation of the space bar lever moves the arm 116 to the right. As a result, when the link 110 is positioned so that the finger 115 can engage the annular member 111 when the arm 116 moves to the right, the connecting link 110 is moved to the right whereby the cable 58 is pulled to return the memory lever 12 into engagement with the stop 17.

The lever 112 is connected to the link 110 through a cable 117, which is slidably supported within a shaft 118 that is fixed against movement. Thus, movement of the control lever 112 in one direction positions the annular member 111 where it can be engaged by the finger 113 while movement in the opposite direction of the control lever 112 disposes the annular member 111 for engagement by the finger 115.

While the memory backspace device of the present invention has been described with respect to a typewriter in which a carriage has a platen movable therewith for carrying the paper for printing with the carriage and platen being movable relative to the printing position, it should be understood that the memory backspace device of the present invention could be utilized with a typewriter of the single element printing head type such as the typewriter shown and described in U.S. Pat. No. 2,919,002 to Palmer. In the aforesaid Palmer patent, the

paper and platen do not move but the carrier having the single element printing head thereon moves. Furthermore, the direction of movement is opposite to that of the carriage. That is, forward relative horizontal movement between the carrier and the reference or printing position at which printing occurs would be to the left in FIGS. 1 and 4 while rearward relative horizontal movement is to the right. Thus, it would be necessary to appropriately design the memory backspace devices to be responsive to movements in the opposite direction.

In a single element printing head typewriter, the movable member 10 would probably be connected to the carrier tape, which moves the carrier and is connected thereto. It is only necessary that the movable member 10 be responsive to the relative horizontal movement between the carrier and the reference or printing position at which the type characters are printed.

While the memory backspace device of the present invention has been described with respect to a typewriter, it should be understood that the device could be employed with any printing apparatus. While the device has been described with respect to a single backspace key movable to two positions, it should be understood that it may be employed with any backspace means of a printing apparatus that will permit backspace operations.

An advantage of this invention is that it is relatively inexpensive and may be easily attached to a typewriter. Another advantage of this invention is that it eliminates the complicated pin wheel memory device for backspacing. A further advantage of this invention is that it permits utilization of a single backspace key for both normal single unit backspacing and automatic backspacing under control of the memory backspace device.

While the invention has been particularly shown and described with reference to preferred embodiments thereof, it will be understood by those skilled in the art that the foregoing and other changes in form and details may be made therein without departing from the spirit and scope of the invention.

I claim:

1. A memory backspace device for a printing apparatus having means movable during each relative horizontal movement between a reference position at which a character may be printed and paper on which the characters are printed and backspace means to cause rearward relative horizontal movement between the reference position at which characters may be printed and the paper on which the characters are printed during each actuation of the backspace means, said device comprising:

means to cooperate with the backspace means for retaining the backspace means in a position for backspace operation;

means to regulate when said cooperating means is moved to a nonretaining position during a backspace operation;

means to control said regulating means to determine when said regulating means moves said cooperating means to its nonretaining position during a backspace operation;

means releasably connecting said control means to the movable means of the printing apparatus to move said control means from a home position in response to forward relative horizontal movement between the reference position at which characters may be printed and the paper on which the characters are printed and to return said control means to its home position when a selected amount of backspacing occurs to move said cooperating means to its nonretaining position during a backspace operation; and

means to return said control means to its home position when a predetermined operation of the printing apparatus occurs after a selected amount of forward relative horizontal movement occurs between the reference position at which characters may be printed and the paper on which the characters are printed.

2. The device according to claim 1 in which said control means is a reciprocating means that reciprocates between its

home position and the position to which it is advanced by the movable means of the printing apparatus.

3. The device according to claim 1 in which additional means returns said control means to its home position when a selected function operation of the printing apparatus occurs irrespective of the amount of forward relative horizontal movement between the reference position and the paper.

4. The device according to claim 1 in which said return means includes means responsive to each selection of a character, said return means returns said control means to its home position during each selection of a character for printing whereby the selected amount of movement is the width of each selected character.

5. The device according to claim 1 in which said return means includes means responsive to each actuation of forward spacing means of the printing apparatus, said return means returns said control means to its home position during each actuation of forward spacing means of the printing apparatus whereby the selected amount of movement is each printed word.

6. The device according to claim 1 including, means to determine the selected amount of movement; said determining means including:

first means responsive to each selection of a character for printing and cooperating with said control means whereby the selected amount of movement is the width of the selected character;

second means responsive to each actuation of forward spacing means of the printing apparatus and cooperating with said control means whereby the selected amount of movement is each printed word; and

third means to render only one of said first and second means operative and to render the other of said first and second means inoperative.

7. A memory backspace device for a printing apparatus having means movable during each relative horizontal movement between a reference position at which a character may be printed and paper on which the characters are printed and backspace means to cause rearward relative horizontal movement between the reference position at which characters may be printed and the paper on which the characters are printed during each actuation of the backspace means, said device comprising:

means to cooperate with the backspace means for retaining the backspace means in a position for backspace operation;

means to urge said cooperating means toward its retaining position;

means connected to said cooperating means for positioning said cooperating means in a nonretaining position whenever said connected means is in a home position;

means releasably connecting said connected means to the movable means of the printing apparatus to move said connected means from its home position in response to forward relative horizontal movement between the reference position at which a character may be printed and the paper on which the characters are printed whereby said urging means moves said cooperating means toward its retaining position; and

means to return said connected means to its home position after a selected amount of movement of said connected means by the movable means of the printing apparatus.

8. The device according to claim 7 in which said return means includes means responsive to each selection of a character for printing whereby the selected amount of movement of said connected means is the width of each selected character.

9. The device according to claim 7 in which said return means includes means responsive to each actuation of forward spacing means of the printing apparatus whereby the selected amount of movement of said connected means is each printed word.

10. The device according to claim 7 including additional means to return said connected means to its home position in response to any of a plurality of function operations of the printing apparatus irrespective of whether said connected means has been moved a selected amount.

11. The device according to claim 7 including, means to determine when actuation of said return means occurs; said determining means including:

10 first means responsive to each selection of a character for printing whereby the selected amount of movement of said connected means is the width of the selected character;

15 second means responsive to each actuation of forward spacing of the printing apparatus whereby the selected amount of movement of said connected means is each printed word; and

20 third means to render only one of said first and second means operative and to render the other of said first and second means inoperative.

12. A memory backspace device for a printing apparatus having means movable during each relative horizontal movement between a reference position at which a character may be printed and paper on which the characters are printed and backspace means to cause rearward relative horizontal movement between the reference position at which characters may be printed and the paper on which the characters are printed during each actuation of the backspace means, the backspace means being movable to a first position in which single actuation of the backspace means occurs and a second position in which automatic repeat operation of the backspace means occurs, said device comprising:

reciprocating means movable from a home position; means releasably connecting said reciprocating means to

the movable means of the printing apparatus to move said reciprocating means from its home position when there is forward relative horizontal movement between the reference position at which a character may be printed and the paper on which the characters are printed;

40 means to return said reciprocating means to its home position after a selected amount of movement of said reciprocating means by the movable means of the printing apparatus;

45 means responsive to movements of said reciprocating means and cooperating with the backspace means of the printing apparatus, said responsive means being movable from a nonretaining position to a second position when said reciprocating means is moved from its home position whereby said responsive means moves from its second position to retain the backspace means in a position for automatic repeat backspace operations when the backspace means is moved to its automatic repeat operation position; and

55 said responsive means having means to retain the backspace means in a position for the automatic repeat backspace operations only when the backspace means is moved to its automatic repeat operation position so that the backspace means can move to its first position for single actuation when said responsive means is in both its non-retaining and second positions.

60 13. The device according to claim 12 in which, said responsive means comprises:

65 a latch biased toward its second position and the position in which it retains the backspace means; and

means connecting said latch to said reciprocating means, said connecting means holding said latch in its nonretaining position when said reciprocating means is in its home position.

70 14. The device according to claim 12 in which said return means includes means responsive to each selection of a character for printing whereby the selected amount of movement of said movable means is the width of each selected character.

15. The device according to claim 12 in which said return means includes means responsive to each actuation of spacing means of the printing apparatus whereby the selected amount of movement of said movable means is each printed word.

16. The device according to claim 12 including means to determine when actuation of said return means occurs; said determining means including:

first means responsive to each selection of a character for printing whereby the selected amount of movement of said reciprocating means is the width of the selected character;

second means responsive to each actuation of spacing means of the printing apparatus whereby the selected amount of movement of said reciprocating means is each printed word; and

third means to render only one of said first and second means operative and to render the other of said first and second means inoperative.

17. The device according to claim 12 in which: said reciprocating means comprises a universally pivotally mounted member;

first resilient means urging said member into engagement with the movable means of the printing apparatus; and said return means comprises:

second resilient means urging said member to its home position; and

means to overcome said first resilient means to remove said member from engagement with the movable means of the printing apparatus whereby said second resilient means returns said member to its home position.

18. The device according to claim 12 in which, said reciprocating means comprises a rotatably mounted member:

first resilient means urging said member into engagement with the movable means of the printing apparatus; and said return means comprises:

second resilient means urging said member to its home position; and

means to overcome said first resilient means to remove said member from engagement with the movable means of the printing apparatus whereby said second resilient means returns said member to its home position.

19. The device according to claim 12 including means to limit the amount of movement of said reciprocating means from its home position by the movable means of the printing apparatus.

20. The device according to claim 12 including additional means to return said reciprocating means to its home position in response to any of a plurality of function operations of the printing apparatus irrespective of whether said reciprocating means has been moved a selected amount.

21. In a printing apparatus having a movable letter feeding part and a backspace key, a memory backspace system

wherein the improvement comprises:

a control member releasably engageable with said letter feeding part;

means supporting said control member for reciprocating movement between a home position and a plurality of effective positions;

means operative in conjunction with each printing operation of said printing apparatus for sequentially disengaging and then engaging said control member with said letter feeding part to move said control member to said home position and then to one of said effective positions, said one effective position being representative of forward movement of said letter feeding part occurring during the conjunctive printing operation;

backspace drive means for moving said letter feeding part in the backspace direction in response to depression of said backspace key; and

means responsive to said effective position of said control member for governing said backspace drive means to move said letter feeding part an amount equal to the forward movement of which said effective position is representative.

22. In a printing apparatus having a movable letter feeding part and a backspace key, a memory backspace system wherein the improvement comprises:

a control member releasably engageable with said letter feeding part;

means supporting said control member for reciprocating movement between a home position and a plurality of effective positions;

operative means to disengage said control member from engagement with said letter feeding part after said control member reaches one of said effective positions and a selected operation of the printing apparatus occurs to return said control member to its home position and then to engage said control member with said letter feeding part for movement by said letter feeding part to one of said effective positions;

backspace drive means for moving said letter feeding part in the backspace direction in response to depression of said backspace key; and

means responsive to said effective position of said control member for governing said backspace drive means to move said letter feeding part an amount equal to the forward movement of which said effective position is representative.

23. The improvement according to claim 22 in which said operative means includes means responsive to each actuation of forward spacing means of the printing apparatus.

24. The improvement according to claim 22 including additional means to disengage said control member from engagement with said letter feeding part when a selected function operation of the printing apparatus occurs irrespective of the position of said control member.

UNITED STATES PATENT OFFICE
CERTIFICATE OF CORRECTION

Patent No. 3,537,564

November 3, 1970

James M. Huckabee

It is certified that error appears in the above identified patent and that said Letters Patent are hereby corrected as shown below:

In the abstract, line 12, "proportioned" should read -- proportional --. Column 2, line 14, "back spacing" should read -- backspacing --. Column 7, line 19, cancel the comma, first occurrence; Column 10, line 18, the colon should be a period. Column 11, line 30, cancel "the actuation of the next"; line 31, cancel "character key results in the ribbon lift". Column 13, line 45 after "mechanism" insert -- results --. Column 15, line 22, the comma should read a colon; line 22, "means" should be the start of a paragraph; line 23, "said" should be the start of a paragraph; line 25, "first" should be the start of a sub-paragraph; line 29, "second" should be the start of a sub-paragraph; line 33, "third" should be the start of a sub-paragraph. Column 16, line 6, the comma should be a colon; line 6, "means" should be the start of a paragraph; line 7, "said" should be the start of a paragraph; line 9, "first" should be the start of a sub-paragraph; line 14, "second" should be the start of a sub-paragraph; line 18, "third" should be the start of a sub-paragraph; line 63, the comma should be a colon; line 63, "said" should be the start of a paragraph; line 65, "a" should be the start of a sub-paragraph; line 67, "means" should be the start of a sub-paragraph. Column 17 line 5, after "including" insert a colon; line 5, "means" should be the start of a paragraph; line 6, "said" should be the start of a paragraph; line 8, "first" should be the start of a sub-paragraph; line 12, "second" should be the start of a sub-paragraph; line 16, "third" should be the start of a sub-paragraph; line 33, the comma should be a colon; line 33, "said" should be the start of a paragraph; line 34, the colon should be a semi-colon.

Signed and sealed this 13th day of April 1971.
